UNITED STATES PATENT OFFICE.

LUTHER D. LOVEKIN, OF ARDMORE, PENNSYLVANIA.

SURFACE CONDENSER.

Application filed May 8, 1923. Serial No. 637,442.

To all whom it may concern:

Be it known that I, LUTHER D. LOVEKIN, a citizen of the United States of America, and resident of Ardmore, county of Montgomery, State of Pennsylvania, have invented a certain new and useful Improvement in Surface Condensers, of which the following is a true and exact description, reference being had to the accompanying drawings, which form a part thereof.

My invention relates to surface condensers and has for its object particularly to provide a condenser from each lateral half of which the cooling water can be cut off at will to permit of the cleaning of the tubes and which, in addition to high efficiency when in full use, will work with very great efficiency when the cooling water is cut off from half of the tubes.

The nature of my improvements will be best understood as described in connection with the drawings in which they are illustrated and in which

Figure 1 is a sectional elevation of my improved condenser taken on the line 1—1 of Fig. 2.

Figure 2 is a cross sectional view on the line 2—2 of Fig. 1.

Figure 3 is a horizontal section in the line 3—3 of Fig. 1.

Figure 4 is a sectional elevation taken on the line 4—4 of Fig. 1, and

Figure 5 is a sectional elevation on the line 5—5 of Fig. 1.

A indicates the shell of the condenser formed so as to provide lateral vertical bypasses indicated at A', A'. A² indicates the opening for the entrance of steam at the top of the shell, A³ the opening at the bottom of the shell for the outlet of condensed water, and A⁴ openings through the ends of the shell for the outlet of air. B is a bank of horizontal tubes located in the upper section of the shell extending, as a belt across the shell but not into the lateral by-pass indicated at A', A', as shown, and preferably the upper tube belt B is divided into sections indicated at B', B', etc. by vertical steam lanes, indicated at C, C, etc. These steam lanes extending, as shown, throughout the depth of the belt though, obviously, they need not extend entirely through the belt. D, D, indicate the lower group of tubes spaced from the sides of the shell by

passages F', F', in free communication with the by-passes A'. Through the center of the

lower tube group extends the air outlet casing G having openings G' for the entrance of air and communicating with the chamber G² from which the air escapes to the air pump, not shown, through the openings A⁴. I form the tube groups D, D, with horizontal steam lanes indicated at C', C', etc. which, in this construction, should not extend entirely through the tube groups but terminate some distance short of the air casing G, as shown. The passages F' are continued, as shown, by contracted passages F² leading into chambers F³ at the bottom of the tube group D, D.

H, H, are dampers provided for opening and closing the lateral steam by-passes indicated at A'. They are secured on shafts H' and operated by levers H² which are held in adjusted positions by the pins on segments H³. I is a head secured at one end of the casing and divided into four chambers K, k, K', k', by the partitions I' and I². I³, I³, are openings for the admission of water to the chambers K, k, and I⁴, I⁴, are passages for the outlet of water from the chambers K', k'. On the opposite end of the shell is secured the header J divided into two chambers L and l by the partition J'.

In normal operation, water is admitted through both water passages I³ into the chambers K and k, from which it passes through the tube groups D, D, into the chambers L and l and thence through the tube group B to the chambers K' and k', and to exit through the passages I⁴. When so operating, the by-passes A' are closed by the dampers H, as shown in Fig. 2.

When it is desired to clean one-half of the condenser, the water is cut off from one of the chambers K or k, so that water only circulates through one lateral half of the condenser and the damper H on this half of the condenser is open so that a portion of the steam will pass through the controlled by-pass A' into the chamber F' without passing through the tube groups B'. The by-pass, of course, must be of such regulated size as to insure that when open it will not take all of the steam but only such portion thereof as can be properly condensed in the tube group D' through which water is passing. The air and any uncondensed steam passing through the tube groups B' into the passage F mixes with the uncondensed steam passing through the by-pass A' into the chamber F' and its continuation F², F³, and

the air and steam is drawn through the corresponding lower tube group D, the horizontal lanes C' facilitating the distribution of the steam through this tube group which, naturally, must have considerable surface area in excess of that which would be necessary or advisable were the condenser intended to operate at all times with cooling water passing through all of its tubes. The rain plate indicated at E not only prevents water of condensation from the upper tube group coming in contact with the lower tube group but also defines the passages F, F', through which the steam and air passing through the upper tube group is guided, into the lateral passages or chambers F'.

Having now described my invention, what I claim as new and desire to secure by Letters Patent, is:

- 20 1. A surface condenser comprising in combination a shell, a group of horizontal tubes extending in a belt across the upper part of the shell and constituting the primary condensing zone, a second group of horizontal tubes arranged in the lower part of the shell, a rain plate situated between the upper and lower tube groups, an air outlet casing located in the lower tube group, one by-pass leading from the top of the shell to the lower part thereof whereby a portion of the steam can be led directly to the lower group of tubes without passing through the upper group, a damper for opening and closing the by-pass, and two separate means for passing cooling water through the upper and lower tube groups whereby the water can be cut off from either lateral side of the condenser at will.
- 25 2. A surface condenser comprising in combination a shell, a group of horizontal tubes extending in a belt across the upper part of the shell and constituting the primary condensing zone, a second group of horizontal tubes arranged in the lower part of the shell, a rain plate situated between the upper and lower tube groups, an air outlet casing lo-

cated in the lower tube group, two by-passes leading from the top of the shell one to each side of the lower portion of the shell, dampers for closing either by-pass at will and two 50 separate means for passing cooling water through the upper and lower tube groups whereby the water can be cut off from either lateral side of the condenser at will.

3. A surface condenser comprising in combination a shell having an opening for the entrance of steam at its top, a group of horizontal tubes extending in a belt across the upper part of the shell, by-passes for steam formed between the side walls of the shell 60 and the upper horizontal belt of tubes, dampers for opening and closing said by-passes at will, a lower group of tubes spaced from the side walls of the shell, an air exit casing located centrally in said lower group 65 of tubes, a rain plate located between the upper and lower tube groups and two separate means for passing water through the upper and lower tube groups whereby the cooling water can be cut off from either 70 lateral side of the condenser at will.

4. A surface condenser comprising in combination a shell having an opening for the entrance of steam at its top, a group of horizontal tubes extending in a belt across the 75 upper part of the shell, said group having vertical steam lanes formed therein, by-passes for steam formed between the side walls of the shell and the upper horizontal belt of tubes, dampers for opening and closing said by-passes at will, a lower group of tubes spaced from the side walls of the shell, said tube group having horizontal steam lanes formed therein, an air exit casing located centrally in said lower group of tubes, 80 a rain plate located between the upper and lower tube groups and two separate means for passing water through the upper and lower tube groups whereby the cooling water can be cut off from either lateral side of the 85 condenser at will.

LUTHER D. LOVEKIN.
